LEER FOR ANNEALING GLASSWARE

Filed Nov. 18, 1927

2 Sheets-Sheet 2

UNITED STATES PATENT OFFICE

VERGIL MULHOLLAND, OF WEST HARTFORD, CONNECTICUT, ASSIGNOR TO HARTFORD-EMPIRE COMPANY, OF HARTFORD, CONNECTICUT, A CORPORATION OF DELAWARE

LEER FOR ANNEALING GLASSWARE

Application filed November 18, 1927. Serial No. 234,146.

This invention relates to leers for annealing glassware, and more specifically to leers of the type embodying a tunnel having means for accurately controlling the temperature gradient at all parts thereof.

Among the objects of this invention are to maintain the walls of a tunnel leer at a uniform temperature across any transverse section. As heat radiation is proportional to the difference of the fourth powers of the absolute temperatures of the ware and the walls, and only the first power of the distance therebetween, all parts of the ware will be maintained at a substantially uniform temperature and even annealing is thereby assured, with the consequent freedom of the ware from internal stresses and strains.

I have found that an excellent way of achieving the results desired is to construct a tunnel leer with one or more helical flues coiled thereabout, preferably two, and preferably also these flues entirely envelope the tunnel and are substantially integral therewith, or at least have a common wall with the tunnel. In order properly to heat a plurality of flues, it may be desirable to use a corresponding number of furnaces, one connected with each of the flues, thus giving great flexibility to the device. An advantage of my helical flue construction is that the flues are continuous, with no abrupt turns in the direction of flow of the gaseous media, and, therefore, the pressure drop of the gases along the flue is minimized.

A further object of the invention is to use various portions of the same flues for heating and cooling respectively, and in order to control the temperature gradient in the tunnel more accurately, to vary at will the relative lengths of the heating and cooling portions. I also contemplate the use of any one of the flues for heating or cooling, as desired, or any combination of the above described methods of operations.

Further objects of the invention are to permit of accurate control of the temperatures at all parts of the leer and to provide for the relative expansion of the various parts.

Other objects and advantages of the pres-

ent invention will be apparent from a reading of the following specification and subjoined claims when taken in connection with the accompanying drawings, in which:

Figure 1 is a diagrammatic side elevation of a leer constructed according to my invention;

Fig. 2 is a section on the line 2—2 in Fig. 1;

Fig. 3 is a section on the line 3—3 in Fig. 1;

Fig. 4 is a section on the line 4—4 in Fig. 1;

Fig. 5 is a section on the line 5—5 in Fig.

1, showing the end of the leer tunnel and draft producing means in elevation;

Fig. 6 is a perspective of the entrance end of the leer with some parts broken away and in section to show the interior construction; and

Fig. 7 is a fragmentary plan view of the delivery end portion of the leer tunnel showing the draft producing mechanism.

In general this invention is directed to the application to a helical flue leer of the various principles and advantages which I have also embodied in other types of leers, such as that shown and described in my Patent No. 1,560,481, granted Nov. 3, 1925.

As diagrammatically illustrated in Fig. 1, the leer comprises a sectional tunnel A; a pair of fire boxes B located respectively above and below the forward or ware-receiving end of the tunnel; a plurality of flues C communicating one with each of the fire boxes and extending in a double helix about the tunnel from end to end thereof; a draft producing device D, specifically a suction fan communicating with both flues; a ware sorting table E located at the exit end of the tunnel; an endless conveyor F, the ware-bearing strand of which traverses the tunnel and the sorting table E and the idle strand of which returns to the entrance end of the tunnel beneath the leer; and a conveyor driving mechanism G.

The several sections of the tunnel are secured together in end-to-end relation and are supported by suitable framework which includes a pair of longitudinally extending channel members 1 and transversely extending channel members 2 which are in turn supported by vertically adjustable pedes-

tals 3. The tunnel may be slightly inclined downwardly from its hot or receiving end to the cool or delivery end to cause a tendency for air to flow through the tunnel, in a direction opposite to that of the movement of the ware. This flow of air through the tunnel is preferably barely sufficient to prevent an inflow of cold air at the hot end of the tunnel without necessarily exerting a material cooling influence upon the ware.

Each of the sections of the tunnel is preferably constructed of cast iron and comprises a substantially cylindrical member 4 having a conveyor supporting member 5 formed in substantially chordal relation thereto preferably by integral supporting portions 6, and two or more semi-annular members, such as 7 and 8, which may be suitably secured together by forming thereon flanges 9 and 10 which may be connected by bolts 11, as illustrated in Figs. 2, 3 and 4. Members 7 and 8 are provided with inwardly directed helical flanges 12 which, together with the outer casings of these members and the cylinder members 4, form a pair of helical passage-ways or flues C completely jacketing the tunnel member 4.

The forward or entrance end of the tunnel is rigidly secured as by bolts 13 (Fig. 6) to the channels 1 of the supporting frame of the leir. The first section, generally indicated at 14, is provided with a closure member 15, forming dead ends at 16 for the flues C, and a plate 17 fixed to member 15 and having an opening 18 the size of the tunnel opening which is desired. The rear end of the first section 14 and each end of the succeeding sections are provided with pairs of bosses 19 in which stub shafts 20 (Fig. 4) are secured, on which are journaled wheels 21 which rest upon rails 22, in turn rigidly fixed to supporting channel members 1. This construction provides for the expansion of the various sections of the tunnel individually and collectively with respect to the support as only the entrance end of the first section 14 is rigidly secured thereto. The tunnel sections 4 may be provided with inturned flanges 23 at either end, leaving an opening 24 to permit the passage of the conveyor and the ware therethrough, these flanges being secured together in any suitable manner, as by bolts 25.

The leir is heated by a pair of similar furnaces B, each comprising a combustion chamber 26 having an opening 27 at one end thereof, into which an oil or gas burner, diagrammatically illustrated at 28, is directed. The combustion chambers are suitably lined with refractory blocks 29 and are provided near their outlet ends with curved baffle members 30 which direct the flames away from the outlets 31 and 34, the opposite walls being semi-circular to direct the products of combustion smoothly into the outlets.

Passages 32 are provided communicating between the outlets 31 and 34 and the atmosphere and are provided at their outer ends with suitable dampers 33 by which the inflow of air may be controlled. Air may be admitted through passages 32 to support secondary combustion and to dilute the products of combustion if it is desired to cool them. The furnace outlets 31 and 34 respectively communicate in a tangential direction with one of the flues C, adjacent to their closed ends 16. The outlets 31 and 34 may be provided with suitable dampers as shown for the purpose of controlling the amount of combustion products admitted to the respective flues. While I have shown and described one particular type of furnace, the invention is not limited to this, but any suitable source of hot media may be used, and if desired, both flues may communicate with a single source of hot media.

Both flues C are open at the exit end of the leir, as shown at 35 (Fig. 5) and are there provided with arcuate dampers 36 mounted upon shafts 37 and provided with suitable adjusting means, as for example, worms 38 cooperating with pinions fixed to the shafts 37, the worms being operable by suitable hand wheels 39.

Cooling air enters the end of the flues C through openings 35, the volume of such air being controlled primarily by dampers 36, the air passing along the flues encircling the tunnel from the cool toward the hot end of the leir and being gradually heated by absorbing heat from the tunnel walls. The distance traveled by this cooling air and the location of the point of change in the direction of flow of the media through the flues C are controlled as hereinafter described.

The flues C are maintained at subatmospheric pressure by means of the suction fan D, which communicates with a conduit 40 extending parallel to the leir from the cooler or exit end for substantially half of its length, although this proportion may be varied if desired. The conduit 40 communicates at intervals along the length of the leir with each of the flues C through independent passages 41, each provided with suitable dampers 42, as illustrated in Fig. 4, controlled by levers 43. These levers may cooperate with a quadrant 44 having a series of notches therein which may be engaged by a suitable spring pressed pivotally mounted detent 45. By suitable regulation of the dampers 42, it is possible to vary the distance which the heated gases travel along the flue and the remaining distance which the cooling air travels from the exit openings 35 in the opposite direction, and also vary the volume of the cooling air, thus controlling the temperature gradient in this portion of the leir.

The hotter portion of the leir at the left of the end of the conduit 40, as shown in Fig.

- 1, is provided with a plurality of spaced temperature controls 46. Each of these controls comprises an inlet opening 47 into each of the flues C, as shown in Fig. 6, the openings 5 47 being provided with dampers 48 and controlling mechanisms 49 corresponding to dampers 42 and the controlling mechanisms 43, 44 and 45. By suitable adjustment of the controlling mechanisms 49, the desired 10 amount of air may be admitted at suitable points along the leer to dilute the hot gases from the furnaces B and thus practically control the temperatures and the temperature gradient within the leer tunnel.
- 15 If desired, only one of the furnaces B may be operated, the other being plugged up in any suitable manner and the dampers 42 and 48 communicating with its flue closed; or if desired, the flue may be used for cooling the 20 leer by opening some of the dampers to admit cooling air either through the end opening 35 or the air controls 46 and the openings 47. In any case, inasmuch as the flues are arranged in helical form entirely enveloping the tunnel, the entire wall of the tunnel at any transverse section may be maintained at substantially an even temperature, so that the radiation of the heat from all parts of the ware to the tunnel, or vice versa, will serve 25 to maintain all parts of the ware at any transverse section at an even temperature and internal stresses may be positively precluded in the finished ware.
- 30 Dissipation of heat from the tunnel and the heating flues may be minimized by surrounding the tunnel with suitable heat insulating material 50, such as powdered kieselguhr or the like. This material may be contained within an outer casing 51 of suitable material, 35 such as sheet metal completely surrounding the tunnel and secured thereto by suitable spacer bolts 52, expansion joints being provided in this outer casing if desired. The insulating material may be of different thicknesses along the tunnel, as is shown in Fig. 45 1, where the part to the left of the joint 53 is of the greater thickness and the part between that joint and joint 54 is of less thickness, the portions of the tunnel to the right of the joint 54 being uninsulated so as to accelerate the cooling of the ware.
- 50 The sorting table E comprises a plurality of spaced parallel longitudinal bars 55 supported at their forward ends by the frame 55 of the leer and at their rear ends by the frame 56 of the belt driving mechanism G. Rollers 57 are carried at spaced intervals by the bars 55 and provide a support for the conveyor as it emerges from the tunnel bearing 60 the annealed ware. The table E is of sufficient length to permit several persons to stand side by side on each side to inspect and remove the ware from the conveyor F for packing. The conveyor F and table E are 65 sufficiently narrow to permit easy access from either side of the table to ware located in the central portion of the conveyor.
- The conveyor F may comprise an endless belt of flexible open structure, the ware-bearing strand of which lies flat upon the cast 70 iron supporting members 5, which constitute the bottom of the leer tunnel, and upon rollers 57 of the receiving table E.
- The conveyor driving mechanism may be of any desired type but preferably is the same 75 as is shown in my Patent No. 1,560,481, granted November 3, 1925, and comprises a pair of geared driving rolls 58 and 59 engaging the belt between them and suitable reducing gears 60 for driving the rolls. Means 80 are provided, as indicated diagrammatically at 61 for taking up the slack in the conveyor belt, such means being fully disclosed in my said patent. From the take-up mechanism 85 61, the idle strand of the conveyor passes over roller 62 and thence beneath the conveyor to its entrance end, it being supported at intervals by rollers 63 suitably mounted upon the pedestals 3. At the entrance end, the belt passes up around roller 64 and thence over 90 roller 65 into the tunnel.
- From the foregoing it will be apparent that I have provided a leer of very rugged and durable construction and one that may be assembled very quickly and easily from a 95 plurality of similar and interchangeable sections. Also it will be apparent that by my construction and method of drawing the heated gases and cooling air through the flues at subatmospheric pressure, the injurious effects of leakage of these media into the tunnel is reduced to a minimum. Furthermore, supporting the tunnel throughout its entire length by anti-friction devices renders it possible to eliminate expansion or other joints 100 between the sections of the tunnel, through which leaks may exist or may develop, and permits the tunnel to expand lengthwise as a unit on its support. By arranging the flues in a helical manner completely enveloping the tunnel, I am enabled to maintain the walls of any transverse section of the tunnel at a substantially even temperature, and thus more accurately to control the transfer of 105 heat to and from the ware.
- 110 Inasmuch as many modifications might be made in my device without departing from the spirit of the invention, I do not wish to be limited except by the scope of the appended claims, which are to be construed as broadly as the prior art permits.
- 115 I claim:
1. A continuous leer for annealing glass-ware comprising a tunnel and a helical flue of good heat conducting material surrounding said tunnel through which media may be passed for controlling and varying the temperatures within the tunnel.
  2. A continuous leer for annealing glass-ware comprising a tunnel, means for moving 125

- the ware therethrough, and a helical flue surrounding said tunnel and extending from end to end thereof through which media may be passed for controlling and varying the temperatures within the tunnel.
5. A continuous leér for annealing glass-ware comprising a tunnel, a source of hot gases, a flue communicating therewith and arranged in helical form about said tunnel, and a draft producing means to maintain said flue at sub-atmospheric pressure.
10. A continuous leér for annealing glass-ware comprising a tunnel, a plurality of furnaces adjacent to the entrance end of said tunnel, and a plurality of helical flues completely surrounding said tunnel from end to end thereof, one of said flues being connected with each of said furnaces.
15. A continuous leér for annealing glass-ware comprising a tunnel, a furnace adjacent to the receiving end of said tunnel, a helical flue surrounding said tunnel and extending from end to end thereof, a duct connecting said furnace with said flue entering the latter in a tangential direction, and means for conveying the ware through said tunnel.
20. A continuous leér for annealing glass-ware comprising a tunnel, a furnace adjacent to the receiving end of said tunnel, a helical flue surrounding said tunnel and extending from end to end thereof, a duct connecting said furnace with said flue entering the latter in a tangential direction, and means for conveying the ware through said tunnel.
25. A continuous leér for annealing glass-ware comprising a tunnel, a furnace adjacent to the receiving end of said tunnel, a helical flue communicating with said furnace and surrounding said tunnel, and an air inlet passage communicating with said flue adjacent to said furnace to supply air for secondary combustion and to dilute the combustion products.
30. A continuous leér for annealing glass-ware comprising a tunnel, a helical heating flue surrounding said tunnel, a plurality of air inlet passages at intervals along said tunnel communicating with said flue, dampers in said passages, and means of creating a draft through said flue and maintaining it at subatmospheric pressure.
35. A continuous leér for annealing glass-ware comprising a tunnel, a helical heating flue surrounding said tunnel, means for causing a heating medium to flow along said flue at subatmospheric pressure, and means located at intervals along said flue for controlling the temperature thereof.
40. A continuous leér for annealing glass-ware comprising a tunnel, a helical flue surrounding said tunnel and extending substantially from end to end thereof, said flue being effective to conduct a heating medium entering at one end and a cooling medium entering at the other end, a single means to cause a flow of both media from their respective ends toward a point intermediate the ends, and means to vary the position of said point longitudinally of the tunnel.
45. A continuous leér for annealing glass-ware comprising a tunnel, a helical flue surrounding said tunnel substantially from end to end thereof, said flue being effective to conduct a heating medium entering at one end and a cooling medium entering at the other end, a single means effective to cause a flow of both media from their respective ends toward a point intermediate the ends, and means located at intervals along said flue for controlling the temperature gradient thereof.
50. A continuous leér for annealing glass-ware comprising a tunnel, a helical heating flue surrounding said tunnel and extending substantially from end to end thereof, said flue being effective to conduct a heating medium entering at one end and a cooling medium entering at the other end, and a single means to cause a flow of both media from their respective ends toward a point intermediate the ends.
55. A continuous leér for annealing glass-ware comprising a tunnel, a helical flue surrounding said tunnel substantially from end to end thereof, said flue being effective to conduct a heating medium entering at one end and a cooling medium entering at the other end, a single means effective to cause a flow of both media from their respective ends toward a point intermediate the ends, and means located at intervals along said flue for controlling the temperature gradient thereof.
60. A continuous leér for annealing glass-ware comprising a tunnel, a helical heating flue surrounding said tunnel, air inlet means located at intervals along said flue, whereby the temperature gradient in the tunnel may be regulated, a draft producing device, a conduit leading thereto along a portion of said tunnel, and a plurality of dampered passages located at intervals along said flue and communicating with said conduit, said flue and conduit being at subatmospheric pressure.
65. A continuous leér for annealing glass-ware comprising a tunnel, a continuous helical heating flue surrounding said tunnel and communicating at its cooler end with the atmosphere through a dampered opening, means located at intervals along the hotter portions of said flue, to admit variable amounts of air thereto, a conduit extending along the tunnel and communicating with the cooler portion of the flue through a plurality of dampered openings, and means communicating with said conduit for creating a draft through said flue and conduit and maintaining both at subatmospheric pressure.
70. A continuous leér for annealing glass-ware comprising a tunnel and a pair of flues surrounding said tunnel in a double helix.
75. A continuous leér for annealing glass-ware comprising a tunnel and a plurality of helical flues completely enveloping said tunnel, each flue extending substantially from end to end thereof.
80. A continuous leér for annealing glass-ware comprising a tunnel and a plurality of helical flues completely enveloping said tunnel, each flue extending substantially from end to end thereof.
85. A continuous leér for annealing glass-ware comprising a tunnel, a helical flue surrounding said tunnel substantially from end to end thereof, said flue being effective to conduct a heating medium entering at one end and a cooling medium entering at the other end, a single means effective to cause a flow of both media from their respective ends toward a point intermediate the ends, and means located at intervals along said flue for controlling the temperature gradient thereof.
90. A continuous leér for annealing glass-ware comprising a tunnel, a helical heating flue surrounding said tunnel, air inlet means located at intervals along said flue, whereby the temperature gradient in the tunnel may be regulated, a draft producing device, a conduit leading thereto along a portion of said tunnel, and a plurality of dampered passages located at intervals along said flue and communicating with said conduit, said flue and conduit being at subatmospheric pressure.
95. A continuous leér for annealing glass-ware comprising a tunnel, a helical heating flue surrounding said tunnel, air inlet means located at intervals along said flue, whereby the temperature gradient in the tunnel may be regulated, a draft producing device, a conduit leading thereto along a portion of said tunnel, and a plurality of dampered passages located at intervals along said flue and communicating with said conduit, said flue and conduit being at subatmospheric pressure.
100. A continuous leér for annealing glass-ware comprising a tunnel, a helical heating flue surrounding said tunnel, air inlet means located at intervals along said flue, whereby the temperature gradient in the tunnel may be regulated, a draft producing device, a conduit leading thereto along a portion of said tunnel, and a plurality of dampered passages located at intervals along said flue and communicating with said conduit, said flue and conduit being at subatmospheric pressure.
105. A continuous leér for annealing glass-ware comprising a tunnel and a pair of flues surrounding said tunnel in a double helix.
110. A continuous leér for annealing glass-ware comprising a tunnel and a plurality of helical flues completely enveloping said tunnel, each flue extending substantially from end to end thereof.
115. A continuous leér for annealing glass-ware comprising a tunnel and a plurality of helical flues completely enveloping said tunnel, each flue extending substantially from end to end thereof.
120. A continuous leér for annealing glass-ware comprising a tunnel and a plurality of helical flues completely enveloping said tunnel, each flue extending substantially from end to end thereof.
125. A continuous leér for annealing glass-ware comprising a tunnel and a plurality of helical flues completely enveloping said tunnel, each flue extending substantially from end to end thereof.

- ware comprising a tunnel, having a pair of continuous flues surrounding said tunnel in a double helix, each of said flues being adapted to conduct temperature controlling media entering each end and passing inwardly of each flue, and means at each end of each of said flues for controlling the passage of media therethrough. 5
18. A continuous leer for annealing glass-ware comprising a tunnel, a pair of continuous flues surrounding said tunnel in a double helix, each of said flues adapted to be connected at one end to a source of heating media and open at their other ends to the atmosphere, and means to cause a flow of the heating media and air inwardly from their respective ends. 10
19. A continuous leer for annealing glass-ware comprising a tunnel, a pair of heating flues surrounding said tunnel in a double helix, and means disposed at intervals along said flues for controlling the temperatures therein. 15
20. A continuous leer for annealing glass-ware comprising a tunnel, a pair of temperature controlling flues surrounding said tunnel in a double helix, dampered air inlet openings disposed at intervals along said flues for controlling the temperature therein, and means to cause the media to flow in said flues at subatmospheric pressure. 20
21. A continuous leer for annealing glass-ware comprising a tunnel, a pair of uninterrupted temperature controlling flues surrounding said tunnel in a double helix, the cooler ends of said flues communicating with a source of cooling medium, and means for causing a flow of heating media through portions of said flues in one direction and the cooling medium through the remaining portions of said flues in the opposite direction. 25
22. A continuous leer for annealing glass-ware comprising a tunnel, a pair of heating flues surrounding said tunnel in a double helix, the cooler ends of said flues communicating with a source of cooling medium, means for causing a flow of heating media through portions of said flues in one direction and the cooling medium through the remaining portions of said flues in the opposite direction, and independent means in each flue for varying the lengths of said portions. 30
23. A continuous leer for annealing glass-ware comprising a tunnel, a pair of heating flues surrounding said tunnel in a double helix, a suction device, a conduit leading along said tunnel, and a plurality of dampered passages communicating between each of said flues and said conduit, whereby to control the effective length of said heating flues and the temperature gradient in said tunnel. 35
24. A continuous leer for annealing glass-ware comprising a tunnel, a pair of uninterrupted temperature controlling flues sur- 40
- rounding said tunnel in a double helix, a plurality of dampered air inlet openings disposed at intervals along each flue, a suction device, a conduit leading therefrom along said tunnel, and a plurality of independent dampered passages communicating between each of said flues and said conduit, whereby independently to control the effective length of said flues and the temperature gradient in said tunnel, said suction device maintaining both flues at subatmospheric pressure. 45
25. A continuous leer for annealing glass-ware comprising a tunnel, a pair of temperature controlling flues surrounding said tunnel in a double helix, means adjacent to the hotter ends of said flues for supplying independently regulable amounts of heating media thereto, a plurality of independent dampered air inlet openings disposed at intervals along each flue, a suction device, a conduit leading therefrom along said tunnel, and a plurality of independent dampered passages communicating between each of said flues and said conduit, whereby to control the effective length of said heating flues and the temperature gradient in said tunnel, said suction device maintaining both flues at subatmospheric pressure. 50
26. A continuous leer for annealing glass-ware comprising a tunnel, a helical heating flue surrounding said tunnel, a furnace adjacent to the entrance end of the leer, a passage for directing the products of combustion from said furnace tangentially into said flue, said tunnel being constructed of a plurality of interchangeable cast iron sections arranged end to end, a support for said leer, means for mounting said sections on said support and permitting their free expansion with respect thereto, and an endless conveyor for moving ware through said tunnel. 55
27. A continuous leer for annealing glass-ware comprising a tunnel, a flue associated therewith and extending substantially from end to end thereof for controlling the temperatures within said tunnel, said flue being effective to conduct a heating medium entering at one end and a cooling medium entering at the other end, a single means to cause a flow of both media from their respective ends toward a point intermediate their ends, and means to vary the position of said point longitudinally of the tunnel. 60
28. A continuous leer for annealing glass-ware comprising a tunnel, a temperature controlling flue associated therewith, air inlet means located at intervals along said flue, whereby the temperature gradient in the tunnel may be regulated, a draft producing device, a conduit leading thereto along a portion of said tunnel, and a plurality of dampered passages located at intervals along said flue and communicating with said conduit, said flue and conduit being at subatmospheric pressure. 65

29. A continuous leer for annealing glass-
ware comprising a tunnel, a heated flue asso-
ciated therewith, means to supply hot gases
to said flue adjacent to the entrance end of
5 said tunnel, air inlet means located at in-
tervals along said flue, whereby the tempera-
ture gradient in the tunnel may be regulated,
a draft producing device, a conduit leading
thereto along a portion of said tunnel, and a
10 plurality of dampered passages located at in-
tervals along said flue and communicating
with said conduit, said flue and conduit be-
ing at subatmospheric pressure.

Signed at Hartford, Connecticut, this 15th
15 day of November, 1927.

VERGIL MULHOLLAND.

29. A continuous leer for annealing glass-
ware comprising a tunnel, a heated flue asso-
ciated therewith, means to supply hot gases
to said flue adjacent to the entrance end of
said tunnel, air inlet means located at in-
5 tervals along said flue, whereby the tempera-
ture gradient in the tunnel may be regulated,
a draft producing device, a conduit leading
thereto along a portion of said tunnel, and a
10 plurality of dampered passages located at in-
tervals along said flue and communicating
with said conduit, said flue and conduit be-
ing at subatmospheric pressure.
